Primary Examiner — Jeffrey D Asch(74) *Attorney, Agent, or Firm* — Banner & Witcoff, Ltd.(57) **CLAIM**

The ornamental design for handset keys, as shown and described.

DESCRIPTION

FIG. 1 is a perspective view of handset keys showing my new design;

FIG. 2 is a front view thereof;

FIG. 3 is a left side view thereof;

FIG. 4 is a right side view thereof;

FIG. 5 is a top view thereof;

FIG. 6 is a bottom view thereof; and,

FIG. 7 is a rear view thereof.

The broken lines in the figures showing the unclaimed portions of a handset are for illustrative purposes only and form no part of the claimed design.
